UNITED STATES PATENT OFFICE.

HENRY H. TALBOYS, OF DULUTH, MINNESOTA, ASSIGNOR OF ONE-THIRD TO ALICE ANDER M. GOW AND ONE-THIRD TO STACY H. HILL, BOTH OF DULUTH, MINNESOTA.

EXCAVATING AND LOADING MACHINE.

1,186,617.

Specification of Letters Patent. Patented June 13, 1916.

Application filed February 10, 1914. Serial No. 817,774.

To all whom it may concern:

Be it known that I, HENRY H. TALBOYS, a citizen of the United States, residing at Duluth, in the county of St. Louis and State 5 of Minnesota, have invented certain new and useful Improvements in Excavating and Loading Machines, of which the following is a specification.

The present invention relates to certain 10 new and useful improvements in excavating and loading machines, and has for its primary object to provide a machine of this character which embodies novel features of construction whereby it can be operated 15 successfully in underground mines and in other similar places where the limitations of space are such as to prohibit the use of ordinary power shovel constructions.

Further objects of the invention are to 20 provide an excavating and loading machine which is light and compact in its construction and can be readily moved from place to place, which will operate in a small amount of space, and which will excavate 25 and loosen the material, swing it over-head and discharge it into a car or like receptacle at the rear of the machine.

The invention also contemplates a machine of this character including a dipper 30 which is constructed without a trap door or other movable part, said dipper being mounted to be swung directly over-head to discharge at the rear of the machine, one edge of the dipper being used for excavating purposes while the dipper discharges 35 at the opposite side thereof.

With those and other objects in view, the invention consists in certain novel combinations and arrangements of the parts, as 40 will more fully appear as the description proceeds, the novel features thereof being pointed out in the appended claims.

For a full understanding of the invention, reference is to be had to the following 45 description and accompanying drawings, in which:—

Figure 1 is a side elevation of an excavating and ore loading machine constructed in accordance with the invention, the dipper being shown by full lines at the beginning of 50 its crowding or excavating movement and by dotted lines in both its initial movement and in its final position which is assumed when discharging its contents into a

car at the rear of the machine. Fig. 2 is a 55 rear end elevation of the machine. Fig. 3 is a top plan view of the machine, portions of the gear casings being broken away to bring out more clearly the gearing between the motors and drive shaft. Fig. 4 is a sectional view showing the worm gearing between the hoisting motor and the transverse shaft. Fig. 5 is a similar view showing the worm gearing between the crowding motor and the transverse shaft, and Figs. 6 and 7 60 are detail views showing different forms of gearing for operating the elevating arms.

Corresponding and like parts are referred to in the following description and indicated in all the views of the drawings by 70 the same reference characters.

Specifically describing the present embodiment of the invention, the numeral 1 designates the bed of the machine which is preferably movably mounted to admit of 75 the machine being readily shifted from one position to another position, the said bed being shown in the present instance as mounted upon a truck 2 which is adapted to travel back and forth upon the track 3. 80

A turn table 4 is mounted upon the bed 1 to revolve about a vertical axis, the opposing faces of the turn table and bed being preferably provided with annular raceways receiving the anti-friction balls 5. 85 Any suitable means may be provided for revolving the turn table or this may be accomplished manually, as in the present instance.

A pair of independent motors 6 and 7 90 are mounted upon opposite sides of the turn table 4, and these motors may be of any suitable type and operated by electricity, compressed air, or steam, as may be most convenient. The motor 7 corresponds somewhat 95 in function to the crowding engine of a steam shovel and the motor 6 to the hoisting engine of a steam shovel.

The shaft 8 of the motor 6 is provided 100 with a worm 9 which meshes with a worm gear 10 on a shaft 11, the said gearing being housed within a suitable gear case 12, while opposite ends of the shaft 11 are provided with pinions 13 which mesh with gear wheels 14 on a transverse shaft 15 105 which is arranged parallel to and under the shaft 11. Rigid with the gear wheels 14 upon opposite sides of the machine are the

hoisting arms 16 which are connected at the outer ends thereof by a transverse shaft 17. A pair of dipper arms 18 are pivotally mounted at the intermediate points in their length upon the extremities of the shaft 17, the said arms being rigidly connected at one end thereof to the dipper 19, and having the opposite ends thereof curved at 18^a for connection with crowding cables 20.

10 The ends of the cables 20 are connected to the grooved periphery of sheaves 21, said sheaves being rigid with gear wheels 22 which are loosely mounted upon opposite ends of the shaft 15 and mesh with gears 15 23 upon a transverse shaft 24 which has a parallel and spaced relation to the shaft 15 and receives power through suitable transmission gearing from the motor 7. A second set of gears 25 are rigid with the shaft 20 24, the said gears 25 meshing with pinions 26 upon an upper shaft 27. The middle portion of the shaft 27 is provided with a worm gear 28 which meshes with a worm 29 upon the shaft 30 of the motor 7.

25 With the foregoing construction, it will be obvious that the motor or engine 6 is connected by gearing to the elevating arms 16 so as to swing the same upwardly and downwardly about the shaft 15 as a pivot 30 center, while the motor or engine 7 is connected by gearing to the sheaves 21 so as to take in or let out the crowding cables 20 and swing the dipper 19 upwardly or downwardly about the shaft 17 at the outer ends 35 of the hoisting arms 16 as a pivot center. The two sets of gearing may be proportioned to obtain any desired ratio of motion between the respective motors and the parts driven thereby. It will also be understood that both motors are reversible and may be operated simultaneously or successively, as may be found necessary.

In Fig. 1 the dipper 19 is shown by full lines in the position B, and by dotted lines 45 in the two different positions A and C. At the beginning of the digging operation the dipper is in the position A, the elevating arms 16 being slightly raised while the dipper arms 18 are substantially vertical. By 50 the operation of motor 6 the hoisting or elevating arms 16 are moved downwardly into a substantially horizontal position, while the motor 7 is operated at the same time to take in the cables 20, thereby drawing downwardly upon the rear ends of the dipper arms 18 and advancing the dipper 19 into the position shown by full lines. The motor 6 is now reversed so as to swing the elevating or hoisting arms 16 upwardly, the 55 ultimate position reached by the dipper being the position C indicated by dotted lines, from which position it discharges its contents into a car or other receptacle (not shown) at the rear of the machine. The 60 dipper is constructed with a solid bottom 65 without any trap door or other movable part and is rigidly connected to the dipper arms 18, so that there is no trip mechanism to be operated and there are no moving parts to get out of order. The edge 19^a of the dipper 70 engages the ore, coal or other material for loosening the same and filling the dipper upon the crowding movement thereof, the contents of the dipper being discharged at the opposite edge 19^b thereof when the 75 dipper is swung overhead into the position C indicated by dotted lines. The turn table 4 may be manually or otherwise operated to swing the dipper from side to side during the excavating and filling movement 80 thereof, so that the dipper will operate for a limited space upon each side of the track 3, although the turn table may be brought back to its original position before the dipper is finally swung upwardly and rearwardly into a discharging position, thereby 85 insuring a proper discharge from the dipper into a car. The advantage of this construction resides in the fact that the dipper 90 is swung directly overhead and discharges 95 into a car at the rear of the machine, thereby enabling the device to be successfully operated in narrow passages where the usual lateral swinging movement of the ordinary power shovel would be impossible. The expense of a trap door and trip mechanism therefor, as well as the additional labor incident to the operation of such a trip mechanism, is also avoided.

A slight modification is shown by Fig. 6, 100 in which the elevating arm 16^b is shown as provided toward the outer end thereof with a pinion 31 which meshes with a gear segment 32 rigid with the frame of the machine. A sprocket 33 which is rigid with 105 the pinion 31 is connected by a sprocket chain 34 to a second sprocket wheel 35 which is rigid with the shaft 15. This shaft 15 would be driven by the motor 6, as in the previous instance, and it will be obvious that 110 rotation of the pinion 31 will cause the same to travel upon the gear segment 32 and swing the hoisting arm 16^b upwardly and downwardly as in the previous instance.

A further modification is shown by Fig. 7, 115 in which the outer end of the hoisting arm 16^c is shown as provided with a pinion 36 which meshes with an internally toothed gear segment 37. A second pinion 38 which is carried by the hoisting arm 16^c meshes 120 at one side thereof with the pinion 36 and at the opposite side thereof with the pinion 39 which is rigid with the shaft 15. As in the previous instance the shaft 15 receives power from the motor 6, and motion is transmitted from this shaft through the train of gears to the pinion 36 so as to rotate the latter and cause it to travel up and down upon the gear segment 37, carrying the hoisting arm 16^c with it.

Having thus described the invention, what I claim as new and desire to secure by Letters Patent, is:—

1. An excavating and loading machine, including a supporting frame, a transverse shaft journaled thereon, a vertically swinging hoisting arm rigid with the shaft and carrying a dipper, a wheel loose on the transverse shaft, an operative connection between the wheel and the dipper, counter-shafts journaled upon the supporting frame and arranged parallel to the transverse shaft, gearing positively connecting one of the counter-shafts and the hoisting arm, gearing positively connecting the other counter-shaft and the wheel, and independent motors geared to the respective counter-shafts for simultaneously swinging the hoisting arm and dipper to impart a crowding movement to the dipper and swing the hoisting arm upwardly and rearwardly to discharge at the rear of the machine. 5
2. An excavating and loading machine, including a supporting turntable, independent motors mounted upon opposite sides of the turntable so as to balance the same, a transverse shaft journaled upon the turntable between the motors, a vertically swinging hoisting arm rigid with the shaft and carrying a dipper, a sheave loose on the transverse shaft, a cable operatively connecting the dipper to the sheave, gearing between one of the motors and the sheave, and gearing between the other motor and the transverse shaft, the hoisting arm being adapted to carry the dipper completely over the top of the machine. 10
3. An excavating and loading machine, including a supporting turn-table, independent motors mounted upon opposite sides of the turn-table so as to balance the same, a transverse shaft mounted upon the turn-table between the motors, a vertically swinging hoisting arm mounted upon the transverse shaft and carrying a dipper, a 15
4. An excavating and loading machine, including a turn-table, independent motors mounted upon opposite sides of the turn-table so as to balance the same, two pairs of superposed shafts extending transversely across the turntable between the motors, the upper shaft of each pair being geared to the respective motor, gearing between the upper and lower shafts of each pair, a hoisting arm rigid with one of the lower shafts and carrying a dipper, a wheel loose on the 20 said lower shaft and geared to the said opposite lower shaft, and an operative connection between the dipper and the wheel. 55
5. A machine of the character described including a supporting frame, a transverse shaft thereon, a vertically swinging hoisting arm rigid with the shaft, a dipper arm pivotally mounted at a point between its ends upon the outer end of the hoisting arm, a dipper applied to one end of the dipper arm, a sheave loose upon the shaft, a cable connecting the opposite end of the dipper arm to the sheave, means for rotating the sheave to swing the dipper arm and impart a crowding movement to the dipper, and independent means for driving the shaft to operate the hoisting arm and swing the dipper completely over the top of the machine. 25 70

In testimony whereof I affix my signature in presence of two witnesses.
